Attorney

UNITED STATES PATENT OFFICE

96,551

DESIGN FOR A COMBINED SWITCH AND FUSE BLOCK

Clarence T. Hollingsworth, Detroit, Mich.

Application February 25, 1935, Serial No. 55,599

Term of patent 7 years

To all whom it may concern:

Be it known that I, Clarence T. Hollingsworth, a citizen of the United States and a resident of Detroit, county of Wayne, and State of Michigan, have invented a new, original, and ornamental Design for a Combined Switch and Fuse Block, of which the following is a specification, reference being had therein to the accompanying drawings.

In the drawings,

Fig. 1 is a front elevational view of the combined switch and fuse block showing my design

on a small scale and illustrating the color contrast of the handles and block;

Fig. 2 is a bottom perspective view of the same with the illustration of color contrast omitted.

The drawings are shaded to show the contrasting color of the handles and front of the block.

I claim:

The ornamental design for a combined switch and fuse block, substantially as shown and described.

In testimony whereof I affix my signature.

CLARENCE T. HOLLINGSWORTH.
